FIG. 5 is a bottom view of one embodiment of the earring shown in FIG. 1;

FIG. 6 is a perspective view of one embodiment of the earring shown in FIG. 1;

FIG. 7 is a front view of the second embodiment of the earring;

FIG. 8 is a rear view of the second embodiment of the earring shown in FIG. 7;

FIG. 9 is a left side view of the second embodiment of

the earring shown in FIG. 7, the right side view being a mirror image thereof;

FIG. 10 is a top view of the second embodiment of the earring shown in FIG. 7;

FIG. 11 is a bottom view of the second embodiment of the earring shown in FIG. 7;

FIG. 12 is a perspective view of the second embodiment of the earring shown in FIG. 7;

FIG. 13 is a front view of the third embodiment of the earring;

FIG. 14 is a rear view of the third embodiment of the earring shown in FIG. 13;

FIG. 15 is a left side view of the third embodiment of the earring shown in FIG. 13, the right side view being a mirror image thereof;

FIG. 16 is a top view of the third embodiment of the earring shown in FIG. 13;

FIG. 17 is a bottom view of the third embodiment of the earring shown in FIG. 13;

FIG. 18 is a perspective view of the third embodiment of the earring shown in FIG. 13;

FIG. 19 is a front view of the fourth embodiment of the earring;

FIG. 20 is a rear view of the fourth embodiment of the earring shown in FIG. 19;

FIG. 21 is a left side view of the fourth embodiment of the earring shown in FIG. 19, the right side view being a mirror image thereof, without a jewelled piece;

FIG. 22 is a top view of the fourth embodiment of the earring shown in FIG. 19;

FIG. 23 is a bottom view of the fourth embodiment of the earring shown in FIG. 19;

FIG. 24 is a perspective view of the fourth embodiment of the earring shown in FIG. 19;

FIG. 25 is a front view of the fifth embodiment of the earring;

FIG. 26 is a rear view of the fifth embodiment of the earring shown in FIG. 25;

FIG. 27 is a left side view of the fifth embodiment of the earring shown in FIG. 25, the right side view being a mirror image thereof;

FIG. 28 is a top view of the fifth embodiment of the earring shown in FIG. 25;

FIG. 29 is a bottom view of the fifth embodiment of the earring shown in FIG. 25;

(Description continued on next page.)

DESCRIPTION

FIG. 30 is a perspective view of the fifth embodiment of the earring shown in FIG. 25;
FIG. 31 is a front view of the sixth embodiment of the earring;
FIG. 32 is a rear view of the sixth embodiment of the earring shown in FIG. 31;
FIG. 33 is a left side view of the sixth embodiment of the earring shown in FIG. 31, the right side view being a mirror image thereof;
FIG. 34 is a top view of the sixth embodiment of the earring shown in FIG. 31;
FIG. 35 is a bottom view of the sixth embodiment of the earring shown in FIG. 31;
FIG. 36 is a perspective view of the sixth embodiment of the earring shown in FIG. 31;
FIG. 37 is a front view of the seventh embodiment of the earring;
FIG. 38 is a rear view of the seventh embodiment of the earring shown in FIG. 37;
FIG. 39 is a left side view of the seventh embodiment of the earring shown in FIG. 37, the right side being a mirror image thereof;
FIG. 40 is a top view of the seventh embodiment of the earring shown in FIG. 37;
FIG. 41 is a bottom view of the seventh embodiment of the earring shown in FIG. 37;
FIG. 42 is a perspective view of the seventh embodiment of the earring shown in FIG. 37;
FIG. 43 is a front view of the eighth embodiment of the earring;
FIG. 44 is a rear view of the eighth embodiment of the earring shown in FIG. 43;
FIG. 45 is a left side view of the eighth embodiment of the earring shown in FIG. 43, the right side being a mirror image thereof;
FIG. 46 is a top view of the eighth embodiment of the earring shown in FIG. 43;
FIG. 47 is a bottom view of the eighth embodiment of the earring shown in FIG. 43;
FIG. 48 is a perspective view of the eighth embodiment of the earring shown in FIG. 43;
FIG. 49 is a front view of the ninth embodiment of the earring;
FIG. 50 is a rear view of the ninth embodiment of the earring shown in FIG. 49;
FIG. 51 is a left side view of the ninth embodiment of the earring shown in FIG. 49;
FIG. 52 is a top view of the ninth embodiment of the earring shown in FIG. 49;
FIG. 53 is a bottom view of the ninth embodiment of the earring shown in FIG. 49;
FIG. 54 is a perspective view of the ninth embodiment of the earring shown in FIG. 49;
FIG. 55 is a front view of the tenth embodiment of the earring;
FIG. 56 is a rear view of the tenth embodiment of the earring shown in FIG. 55;
FIG. 57 is a left side view of the tenth embodiment of the earring shown in FIG. 55, the right side being a mirror image thereof, without a jewelled piece;
FIG. 58 is a top view of the tenth embodiment of the earring shown in FIG. 55;
FIG. 59 is a bottom view of the tenth embodiment of the earring shown in FIG. 55;
FIG. 60 is a perspective view of the tenth embodiment of the earring shown in FIG. 55;
FIG. 61 is a front view of the eleventh embodiment of the earring;
FIG. 62 is a rear view of the eleventh embodiment of the earring shown in FIG. 61;
FIG. 63 is a left side view of the eleventh embodiment of the earring shown in FIG. 61, the right side view being a mirror image thereof;
FIG. 64 is a top view of the eleventh embodiment of the earring shown in FIG. 61;
FIG. 65 is a bottom view of the eleventh embodiment of the earring shown in FIG. 61;
FIG. 66 is a perspective view of the eleventh embodiment of the earring shown in FIG. 61;
FIG. 67 is a front view of the twelfth embodiment of the earring;
FIG. 68 is a rear view of the twelfth embodiment of the earring shown in FIG. 67;
FIG. 69 is a left side view of the twelfth embodiment of the earring shown in FIG. 67, the right side view being a mirror image thereof;
FIG. 70 is a top view of the twelfth embodiment of the earring shown in FIG. 67;
FIG. 71 is a bottom view of the twelfth embodiment of the earring shown in FIG. 67; and,
FIG. 72 is a perspective view of the twelfth embodiment of the earring shown in FIG. 67.

UNITED STATES PATENT AND TRADEMARK OFFICE
CERTIFICATE OF CORRECTION

PATENT NO. : Des. 354,016
DATED : January 3, 1995
INVENTOR(S) : Thomas SCHUBERT

It is certified that error appears in the above-identified patent and that said Letters Patent is hereby corrected as shown below:

On the title page, after item [22], insert the following Foreign Priority Data:

-- [30] Foreign Application Priority Data
February 22, 1991 [DE] Fed. Rep. of Germany
DM/018939--.

Signed and Sealed this
Fifteenth Day of October, 1996

Attest:

BRUCE LEHMAN

Attesting Officer

Commissioner of Patents and Trademarks
